DESIGN FOR A COMBINED LOVE-SEAT AND CHAIR OR SIMILAR ARTICLE

Joseph B. Nathan, New York, N. Y.

Application October 26, 1934, Serial No. 53,770

Term of patent 3½ years

To all whom it may concern:

Be it known that I, Joseph B. Nathan, a citizen of the United States, residing in the county of Bronx, city and State of New York, have invented a new, original, and ornamental Design for a Combined Love-Seat and Chair or Similar Article, of which the following is a specification, reference being had to the accompanying drawing, forming part thereof.

The figure is a perspective view of a combined love-seat and chair or similar article showing my new design.

I claim:

The ornamental design for a combined love-seat and chair or similar article as shown.

JOSEPH B. NATHAN.
